DESIGN FOR AN AIR TUBE FOR OIL BURNERS OR THE LIKE

Reginald W. Beckett, Elyria, Ohio

Application December 15, 1938, Serial No. 81,787

Term of patent 14 years

To all whom it may concern:

Be it known that I, Reginald W. Beckett, a citizen of Canada, residing at Elyria, in the county of Lorain and State of Ohio, have invented a new, original, and ornamental Design for an Air Tube for Oil Burners or the like, of which the following is a specification, reference being had to the accompanying drawing, forming a part thereof.

In the drawing:

Figure 1 is a perspective view of an air tube for oil burners or the like, showing my new design; and

Figure 2 is a front end view thereof.

I claim:

The ornamental design for an air tube for oil burners or the like, substantially as shown.

REGINALD W. BECKETT.
